UNITED STATES PATENT OFFICE.

MATHIAS FOGDE AND LAWRENCE P. SOUTHWICK, OF RICHMOND, VIRGINIA.
ASSIGNORS, BY MESNE ASSIGNMENTS, TO STOKES & SMITH COMPANY, OF
PHILADELPHIA, PENNSYLVANIA, A CORPORATION OF PENNSYLVANIA.

LABEL OR STAMP APPLYING APPARATUS.

Application filed May 23, 1919. Serial No. 299,284.

To all whom it may concern:

Be it known that we, MATHIAS FOGDE and LAWRENCE P. SOUTHWICK, respectively a subject of the Government of Russia and a citizen of the United States, residing at Richmond, in the county of Henrico and State of Virginia, have invented new and useful Improvements in Label or Stamp Applying Apparatus, of which the following is 10 a specification.

This invention relates to improvements in label or stamp applying apparatus, pertaining more particularly to the preparation and conditioning of the stamp or label preparatory to its application to the package to be stamped or labelled.

While the present invention is adapted for use in various connections, it is more particularly adapted for use in connection with 20 apparatus of the general type disclosed in the patent granted to us October 23, 1917, No. 1,244,438, a use in which a plurality of stamps or labels are applied concurrently to a corresponding number of packages or containers, the general idea in this respect being to produce the effect of a "gang" operation on a plurality of containers.

Where apparatus of this type is used for the stamping of containers of tobacco products—as for instance boxes of cigarettes—the stamps are of the usual revenue type, supplied in the form of sheets formed of rows extending longitudinally and transversely of the sheet. Since the operation is 30 designed as a gang operation, the general apparatus is based on the use of one of the rows of the sheet for each operation of the apparatus, and in the particular embodiment shown, the stamps of the transverse row are 35 utilized, thus bringing the direction of length of the stamp corresponding to the front to rear direction of the stamp feed operation. Since the stamps are connected together side by side in the sheet form, and 40 each stamp has a width less than the width of the container, it becomes necessary not only to separate the row of stamps into its individual stamp formation, but, in addition, to advance the stamps in such manner that 45 when in the applying position each stamp 50 will be properly positioned with respect to

the container to which it is to be applied. An apparatus for producing this effect is disclosed in the prior patent referred to, the means employed being in the form of a 55 stamp transporting means made up of a proper number of individual stamp carriers, the carriers being arranged to pick up the stamps in their normal relation to each other in the row supplied, the loaded carriers then 60 advancing to the applying position with the apparatus so arranged as to cause the carriers to spread apart during their advancing movements, the apparatus being so designed as to provide independent paths of movement 65 of the carriers to bring about this result. When the stamps have been advanced into applying position, the carriers are lowered into contact and portions of each stamp applied, after which the remaining portions of 70 the stamp are applied in suitable manner and then the entire row of containers—which may be considered as a charge—is removed from the apparatus concurrently.

The rows of stamps are prepared or conditioned during the advancing travel of the carriers, and it is to this general portion of the apparatus cycle that the present invention more particularly relates, the particular preparation and conditioning consisting in 75 subjecting the row of stamps, which has been picked up by the carriers, to a slitting action and then applying adhesive to the exposed face of each stamp, this preferably taking place in advance of the carrier separating 80 action, so that the stamps are advancing in parallel lines during this preparing operation.

For the purpose of a practical and economical operation, the carriers are arranged to have their advancing movements in a single horizontal plane, the carriers being shifted from this plane at the opposite extremes of movement of the carrier, the shifting movements being downward from such 95 plane in order to pick up a row of stamps at one end of the transporting movement and to apply the conditioned stamps at the opposite end of the movement. And it is preferred that pneumatic means be employed 100 for the purpose of retaining a stamp in position on its carrier, the apparatus being ar-

ranged to admit suction to a carrier at the time the stamp is picked up, and to break the suction at the time when the stamp is to be applied.

5 Since the travel of the carriers is in the same plane both during the advance and the retreat movements, certain problems are involved in connection with the application of the adhesive, it being readily understood 10 that since the face of a carrier travels in the same plane, provision is necessary to prevent the application of the adhesive to an uncovered face of a carrier, such face being uncovered in each retreat movement 15 of the carrier and possibly during a forward movement in the case of a failure of the carrier to pick up its stamp. The problems present will be understood by considering the fact that since the adhesive application mechanism is located at an intermediate 20 point in the travel of the carriers—becoming operative after the stamps have been slit and being completed in advance of the separating movement of the carriers—each 25 carrier must pass the adhesive applying station both during the advance and the retreat movements of the carrier.

Another problem to be met is the character of the adhesive coating to be applied, it 30 being understood that an excessive amount of adhesive will tend to bring about a condition of coozing of the surplus adhesive during the stamp application and thus not only 35 tend to bring about difficulties in the applying operation through the presence of adhesive on the applying devices, but also spread the adhesive onto exposed surfaces 40 of the containers with result that when such surfaces are brought into contact with surfaces of other containers, there is a liability 45 of sticking together of the contacting containers. Hence the problem of the character of the adhesive coating must be met, and in the present invention, this is met by not 50 only controlling the character of the coating of the adhesive applying element but also by controlling the position of the coating on the stamp in order that this oozing 55 may be prevented.

50 The objects of the present invention are, therefore, to provide an apparatus capable of meeting these problems as well as other problems presently referred to, in a simple and efficient manner, and by a structure 55 which is durable in construction and of comparatively low cost.

To this and other ends, therefore, the nature of which will be readily understood as the invention is hereinafter disclosed, said 60 invention consists in the improved construction and combination of parts hereinafter more fully described, illustrated in the accompanying drawings, and more particularly pointed out in the appended claims.

65 In the accompanying drawings, in which

similar reference characters represent similar parts of each of the views,—

Figure 1 is a section through a preferred form of apparatus employing the particular invention herein disclosed, the section being 70 taken on a plane corresponding to the general advance direction of movement of a stamp.

Figure 2 is a top plan view of portions of the apparatus disclosed in Figure 1. 75

Figure 3 is a top plan view showing the slitting and adhesive applying mechanisms.

Figure 4 is a detailed section of the carriage similar to Figure 1, but with the carriage in different position, showing the emergency release for the gluing device. 80

Figure 5 is a detailed sectional view of parts of the adhesive applying mechanism.

Figure 6 is a view partly in section and partly in elevation showing a control element for the adhesive applying mechanism. 85

Figure 7 is a perspective view of a conditioned stamp.

Fig. 8 is an enlarged detail, partly in section, of the suction valve and operating mechanism. 90

Referring to Figure 1, 10 designates a supporting bed of the general frame of the machine and above which and supported on suitable pedestals 11 are guides 12 of suitable form and within which the stamp or label transporting means is adapted to reciprocate. 13 indicates a plate of suitable configuration positioned generally in planes above guides 12, plate 13 being provided 95 with guide slots 13^a which control the movements of the stamp carriers as the latter are advanced and retracted. These elements are stationary and are arranged and have such relation that the guides 12 and plate 13 are 100 located above the slitting and adhesive applying mechanisms, the latter being positioned on bed 10.

For the purposes of the present disclosure, the carriers are not described in detail, one 110 of them being shown more particularly at 14 in Figure 4 as consisting of a carrying head 14^a having a central cut-away portion to provide advance and rear portions, the interiors of which are adapted to be placed in 115 open communication with a suction line indicated generally at 15, the several lines having connection with a hollow rod 16 extending transversely of the apparatus above plate 13 and which is connected to a suitable 120 source of suction (not shown) through a connection 17, member 16 being provided with a control mechanism 18 presently described. Each head 14^a is supported on a vertically extending member 14^b which may 125 form a conduit to the suction line, said member extending through a guide member 14^c shiftable laterally in guides 19, the latter being carried by the reciprocating transporting means. Member 14^b also carries an 130

element 20 adapted to travel in one of the guide slots 13^a. Head 14^a is normally held in its upward position by means of a spring 14^d located between element 20 and a collar 14^e carried by the member 14^b.

The transporting element is in the form of a frame 21 having portions extending into guides 12 and which carries standards for supporting suction members 16 and guides 19 which may be formed integral with the frame, guide 14^c having depending stems on which head 14^a may be reciprocated. As shown in Figure 2, the transporting means also carries a control element presently referred to.

During the advancing and retreating movements of the transporting means, the carrier travels with its head in the upward position. However, the apparatus has means 20 designed to shift the position of the heads when the carriers are at the extremes of their transporting movements. This means is shown as in the form of a pair of elements 22 and 23, located respectively at the front 25 and rear of the apparatus, each element being mounted to reciprocate vertically in suitable manner as by the use of cams, each element being individually controlled by its cam. As shown, each element is provided 30 with a plurality of slots opening toward the direction of approach of the carriers, each recess being adapted to receive the collar 14^e of a carrier. Since the spacing of the collars relative to each other varies at the front 35 and rear of the apparatus, it will be understood that these recesses will be suitably spaced accordingly. Elements 22 and 23 are normally in their upper position which places the recesses in alignment with collar 40 14^e, which latter is provided with an annular groove within which the walls of the recesses may enter, the latter thus tending to form fingers which enter the groove. After the carriers have reached this position, element 22 or 23, as the case may be, is shifted 45 downwardly, thus moving member 14^b downward against the tension of spring 14^d—as shown for instance at the right of Figure 1—thus shifting head 14^a downward, the head 50 then being returned to normal position by the return travel of the element 22 or 23 which is in operation at the time.

The downward travel of the carrier heads is had when the carriers are above the stamp receptacle 24—at which time element 23 is 55 made active—and when the carriers are in position above the containers to which they are to be applied, this latter being the position in which element 22 is active.

60 Through the slidable lateral movement of member 14^c, the heads 14^a are permitted to shift laterally during the advance and retreating movements without liability of damage to the structure.

65 The stamp receptacle 24 is mounted on

bed 10 and is arranged in such manner as to automatically retain a stamp or label in the approximate plane of the heads 14^a when the latter are shifted downwardly by element 23. Any suitable mechanism may be 70 employed for this purpose, as for instance, by the use of a vertically movable table 24^a within the receptacle and on which the stamps are located in pack formation, the table being connected up in suitable manner with a weight which tends to raise the table. Our prior patent above identified indicates a structure of this kind, means being provided for limiting the upward movement of the pack; the table is yieldable in the 80 presence of downward movement of heads 14^a, thus providing a compensating structure and at the same time assuring that the heads are in contact with the row of stamps—unsevered from each other at this time—and 85 will permit of proper location on the heads through the application of suction action.

The control of suction activity to the heads 14^a is by the use of a suitable control mechanism 18 which is in the form of a 90 valve, shown as of the turning-plug type, the stem of which carries a pinion 18^a adapted to engage a lever 18^b which itself carries a tooth segment 18^c engaging said pinion 18^a, said lever having a pair of laterally projecting members 18^d and 18^e so located as respectively to pass beneath an actuating member 22^a carried by element 22 and a similar member 23^a carried by element 23, the arrangement being such that when member 18 is in its rear position, the downward movement of element 23 will cause its member 23^a to engage such lever element 18^d and rock the lever a distance sufficient to rotate the turning plug of the valve and open the 100 latter to the suction line, thus applying suction to the suction heads when the latter are in contact with the uppermost stamp of the stamp receptacle.

The suction remains active until the lever 110 is rocked in the reverse direction, and this takes place when member 16 passes to a position where the other projection 18^e of the lever is located beneath member 22^a, the downward movement of element 22 operating to rock the lever and shift the valve to closed position, this condition then being maintained until the valve is again opened by the operation of member 23^a.

This arrangement thus renders the suction 120 active during the advancing movement of the transferring mechanism and inactive during the retreating movement of the latter, the opening or closing of the valve taking place when the heads are in their lower 125 positions.

The transferring device is reciprocated in any suitable manner, as by the use of a pitman 25 connected up to a suitable operating mechanism adapted to move the pitman in 130

directions to advance and retract the transferring mechanism.

The stamp or label preparing mechanism is located between the bed 10 and the path 5 of travel of the transferring mechanism and between the positions of the stamp receptacle and the point where the stamp is applied. This preparing mechanism substantially embodies two mechanisms, one of 10 which is adapted to slit the row of stamps into its individual stamp units without disturbing the position of the stamps on the heads 14^a; the other mechanism is an adhesive applying mechanism which is adapted to 15 provide a coat of adhesive onto the exposed face of the individual stamps while the carriers are advancing toward the front of the apparatus.

The slitting mechanism embodies a rotatable shaft 26 on which are mounted a plurality of disks 27 having a knife or saw edges, these extending into the plane of the path of travel of the stamp row as the latter is advanced, the arrangement being such that 20 as the carriers advance the stamp strip or row is carried past these disks, the latter being adapted to sever one stamp from the other, it being understood, that the disks will be positioned to have their cutting or 25 sawing edges operative at the proper points in the length of the stamp strips.

Shaft 26 may be rotated in any suitable manner, a preferred arrangement, however, being shown in Figure 3 in which 28 indicates a suitable power source shown as in the 30 form of a sprocket which is operatively connected to the main drive shaft of the apparatus, said sprocket being mounted on a shaft carrying a bevelled gear 29 in mesh 35 with a bevelled gear 30^a operatively connected with a gear 30 loosely mounted on a stud 31; obviously stud 31 may be in the form of a shaft, in which case gear 30 would be secured thereon. Gear 30 is adapted to 40 drive a pinion 32 carried on a stub shaft which also carries a gear 33, the latter in turn being in mesh with a pinion 34 mounted on shaft 26, the result being that shaft 26 is rotated at a comparatively high speed and 45 thus insure proper severing action on the advancing stamp strip.

The carriers 14 are so positioned as to provide a sufficient space between them in the rear positions of the transfer mechanism 50 as to permit the slitting disks to properly operate within the intermediate spaces.

The adhesive applying mechanism is located in advance of the slitters just described, and this adhesive mechanism is also 60 operative on the advancing stamps prior to the time the carriers begin the spreading movement. This adhesive applying mechanism includes a supply receptacle 35, a supply roller 36 mounted in bearings on the 65 receptacle and being adapted to extend into

the receptacle contents, the receptacle also carrying a suitable scraper 36^a for removing surplus adhesive from the face of roller 36.

The adhesive is applied to the stamps by means of a rotatable element which includes 70 a segment 37 carried by the element shaft 38, the face of segment 37 being so positioned as to have a path of movement which causes the segment face to pass into contact with the coated face of roller 36 and also 75 into contact with the passing stamps mounted on the carrier heads, the segment receiving its supply of adhesive from roller 36 and in turn applying it onto the exposed faces of the advancing stamps. 80

Shaft 38 is driven in suitable manner, Figure 3 showing the drive as from gear 30, but, for purposes presently pointed out, the connection includes a coupling structure 85 presently described which permits the rotative movement of the shaft to be prevented without affecting the operation of the transfer mechanism, this cessation of rotation being permitted under certain conditions; roller 36 is preferably driven from shaft 38. 90

The particular form of drive connections for shaft 38 shown in the drawings is designed to meet certain conditions; the particular embodiment which may be employed may be varied from that disclosed, it being 95 preferred, however, that the mechanism which may be employed will produce a general operation such as will meet the conditions now to be described.

As will be understood, the length of an 100 individual stamp is relatively short as compared with the length of travel of the transporting mechanism in completing one cycle, the time required for the cycle being increased by reason of the dwell in the movement of the transferring mechanism which 105 takes place at the ends of the advance and retreat movements and during which the carrier heads are given their vertical movements. Hence it will be understood that the 110 particular length of time required for active contact of the face of segment 37 with the stamp is but a small portion of the time required to complete this cycle, the length of such cycle being increased by reason of the 115 fact that provision must be made for the separating of the carriers in order to produce the proper positioning of the stamps on the containers. And while this length of time of contact is small, it will be understood that it is essential that the angular 120 speed of travel of the segment be made substantially equal to the advancing speed of travel of the carriers at this time in order that the possibility of disturbing the position of the stamp on the carrying head be reduced to a minimum.

To meet this particular condition, we arrange the drive mechanism for shaft 38 in such manner that the segment will normally 130

- rotate more than once during each cycle of the transferring mechanism, the arrangement, in actual practice, providing for a plurality of such revolutions of shaft 38 during this period. This arrangement permits of retaining the proper angular length of the segment and at the same time retain the size of the parts comparatively small and hence permit of the use of a general compact structure. As will be understood, no portion of this applying structure, with the exception of the applying face of the segment, passes into the path of movement of the carrying head faces, so that it is only when such face of the segment is in its upper position that possibility of contact with the head faces is had, and this possibility is limited only to times when the head faces and the segment face are in the proper positions. Consequently the position of the mechanism can be readily arranged as to insure that during the period of advance of the stamps on the heads 14^a, the segment face will be brought into activity to produce a proper application of adhesive to the advancing stamps, while during the return movement of the carriers, the position of the segment will be such as to be out of the paths of movement of the head faces during the period when the carriers are passing the zone of activity of the segment, thus providing against applying a coat of adhesive onto the head faces or portions of the face.
- This result can be obtained by a proper timing of the connections between gear 30 and shaft 38 and at the same time provide for the travel at substantially equal speeds of the segment face and the carrier head faces.
- However, there is the possibility of an occasional difficulty in the operation of the apparatus, a difficulty which may be brought about by the failure of proper location of a stamp or a row of stamps on the carrier heads, it being understood, of course, that the apparatus is operating under suction conditions and that improper positioning of a stamp sheet in the stamp receptacle or various imperfections may bring about a condition where failure is had to properly position all of the stamps on the respective heads as the carriers are being advanced. Under such conditions it is possible that one or more of the carrier faces would remain exposed and therefore in position to receive adhesive from the segment as the latter is brought into activity in the normal cycle of operation of the apparatus.
- By providing a plurality of rotatable movements to the segment during the single cycle of the transferring mechanism, we are able to meet this possible condition as a part of the general drive connections of shaft 38, permitting the segment to have its usual cycle in the absence of any abnormal conditions and yet temporarily disturb this cycle in the presence of such abnormal conditions, providing this result automatically through the use of a suitable detecting mechanism of simple form. This change in the cycle of the segment is produced by eliminating one of the rotations of the segment when such abnormal conditions are present, the segment thus remaining stationary during the time when the carriers are traversing the zone of activity of the segment in the advancing direction of the carriers.
- A simple form of mechanism for producing these results is shown in the drawings, but it will be understood that the type disclosed is more or less illustrative and may be varied as may be found necessary. The mechanism shown will now be described.
- 39 indicates a gear wheel loosely mounted on a shaft 40, gear 39 meshing with gear 30 heretofore described. Gear 39 is provided with a hub carrying a notch or recess 39^a which is adapted to receive the tooth of a pawl 41 pivotally supported by an arm 42 mounted on and rotatable with shaft 40, the pawl being spring actuated with the spring operative to normally retain the tooth of the pawl in engagement with the recess 39^a. Since gear 39 is constantly rotated, it will be understood that as long as pawl 41 engages notch 39^a, shaft 40 will be constantly rotated, and if shaft 40 be positively connected to shaft 38—the two shafts may, if desired, be a single shaft—a direct and constant drive will be had from gear 30 to shaft 38. In the drawings, shafts 40 and 38 are shown as separate and connected by a suitable coupling 43.
- As will be understood, however, if pawl 41 is rocked on its pivot so as to disengage its tooth from notch 39^a, the drive engagement between gear 39 and shaft 40 will be broken and the shaft will remain stationary until this engagement of pawl and notch is again provided. This engagement of pawl and notch is not disturbed excepting in the presence of such abnormal conditions, and the disengagement which takes place at such time is maintained only during one revolution of gear 39, pawl 41 being held out of the path of travel of the notch for a period sufficient to insure that, when released, it will contact with the face of the hub and ride thereon—remaining stationary with shaft 40—until the succeeding arrival of the notch places it in position where the pawl spring becomes effective to cause the tooth to reenter the notch, whereupon the normal drive connection is resumed.
- The control of such disengagement movements is placed on a control mechanism carried by and movable with the transferring mechanism, being of such form and position that disengagement, when brought about, is had when the segment is out of

its zone of activity, thus retaining it out of such zone until gear 39 has made its single revolution, a sufficient period to permit the transfer mechanism to advance out of the 5 zone of activity of the segment, the reengagement of pawl and notch restoring the normal operating conditions.

This control mechanism is in the form of a lever 44 pivotally supported on the 10 transferring mechanism frame, said lever having an arm 44^a projecting in the direction of travel of said mechanism, lever 44 having its axis extending in the same direction and thus substantially parallel with 15 the direction of length of this arm. The opposite end of said lever carries an arm 44^b connected to a flexible diaphragm 45 which forms one wall of a cavity 46 formed in said frame and which is in open communication with member 16, thus placing this 20 cavity as a part of the suction line. Lever 44 is of the spring actuated type, spring 47 being adapted to normally hold the lever in such position that the diaphragm is in 25 an outward position, this particular position of the parts being indicated in full lines in Fig. 6 which also shows in dotted lines the inactive position of arm 44^a. When the chamber 46 is connected to the suction 30 source, lever 44 is rocked so that arm 44^a will be held out of the path of pawl 41, consequently the connection between the driving mechanism and segment 37 will not be broken while the suction source is actively 35 connected to chamber 46, a condition which exists during the forward movement of the picker, only when all the stamps are properly registered thereon. If, however, a stamp be displaced or missing, the suction 40 will be released into the picker and arm 44^a and be rocked by spring action into the path of pawl 41 thereby releasing the connection between the driving means and the segment and rendering the latter in- 45 active during the passage of the pickers thereover.

If desired, valve 18 may be so constructed that when it is turned to cut off suction connection to the pickers the vent through the 50 valve casing to the outer air is connected to header 16 so as to release the residual suction in the header and pickers and effectually release the stamps carried by the pickers.

Since shaft 40 has its movements in synchronism with those of shaft 38, it will be understood that the same factor of timing to prevent conjunction of pawl 41 and arm 44^a may be provided in the manner referred to in connection with the segment 60 so far as the return portion of the cycle is concerned.

However, during the advancing movement of the transferring mechanism, these two elements are brought into a relation 65 which will permit the disconnecting action

provided arm 44^a remains in the same vertical plane as the path of travel of the pawl. Under these conditions, arm 44^a advancing in the direction of the arrow in Figure 4 and the pawl arm travelling counter-clockwise in the same figure, it will be seen that the tail of the pawl passes into contact with the arm 44^a as arm 42 rotates, and as said latter arm continues its rotation, the relative positions of arm 44^a and pawl cause 70 the pawl to be rocked on its pivot until its tooth disengages from the notch, whereupon gear 39 continues its rotation without effect on the pawl, shafts 38 and 40 remaining stationary and arm 44^a continuing 75 its advance until it passes out of contact with the tail of the pawl whereupon the latter is rocked in a return direction and brings its tooth into contact with the face of the hub of gear 39 on which it rides 80 until the hub rotation brings notch 39^a 85 opposite the tooth of the pawl when reengagement is had.

As will be understood, should lever 44 be rocked on its pivot so as to carry arm 44^a laterally out of the vertical plane of the pawl travelling path, arm 44^a and the pawl will not be brought into conjunction although each of these parts have their usual advancing movements, the result being that 95 the pawl will not be disengaged at this point and shaft 40 will be continuously rotated.

The position of lever 44 at this time is controlled by conditions in the carrier head. 100 Should each of the heads have its ports to the suction line properly closed by a stamp no air will enter into the suction line and feed the latter through these ports, and the stamps will be held to the faces of 105 the heads; in such case, however, cavity 46—also open to the suction line—provides a limited supply of air, the withdrawal of which under the action of suction affects the position of diaphragm 45 and tends to 110 draw the latter inward to the position shown in dotted lines in Figure 6, the result being that lever 44 is rocked pivotally and moves arm 44^a out of the path of travel of pawl 41, the engagement of the pawl tooth and its notch remaining undisturbed and the normal operation of the rotating segment carrier being continuous. When the applying station is reached and the suction line is broken by the closing of the 115 valve, the release of the stamps from the ports opens up the head ports to the entrance of air, thus feeding air to the entire line beyond valve 18 rendering spring 47 active to return lever 44 to its normal 120 position.

Should, however, head ports be open through abnormal conditions of a stamp or stamps, it will be readily understood that such ports will provide an air supply to 125 130

the suction line and thus render the suction inactive in cavity 46, such inactivity preventing action on diaphragm 45 and leaving lever 44 in its normal position with arm 5 44^a extending in the vertical plane of the path of travel of the pawl, bringing about the conjunction of said arm or pawl and disengaging the pawl tooth from its notch, this disengagement continuing until gear 39 10 has made a complete revolution when engagement is restored and the parts continue in their ordinary relation.

It will be understood, therefore, that in the particular embodiment shown, the arrangement provides for a normal position of parts in which disengagement of pawl and notch is inherent, and this normal condition is disturbed only when the apparatus is in its desired operative condition with 20 the stamps or labels properly positioned, the latter thus forming a control means by which lever 44 is moved from its normal position to pass by the pawl as the latter advances. This movement of the lever on 25 its pivot is the normal operation, thus providing a regular cycle of movement to the lever under normal conditions of operation of the apparatus itself, this normal cycle of operation of the lever being varied only 30 under abnormal conditions in the apparatus itself, so that the lever is normally set to prevent adhesive application of the suction heads, and will remain in this position under all conditions excepting such as provided for the desired operation.

As heretofore pointed out, one of the problems to be met is the possibility of the adhesive oozing out when the label or stamp is being applied to the commodity container. 40 This problem is met by not only controlling the amount of adhesive which is applied to the surface of the stamp or label, but through additional control of the particular location of the adhesive on the stamp or label. This combined control is provided in 45 the following manner:

As heretofore pointed out, the amount of adhesive which is exposed on the face of roller 36 at the time that segment 37 contacts with the roller is controlled within certain limits by the scraper 36^a, so that the adhesive coat on roller 36 is practically uniform as to thickness and distribution. Hence when the active face of the segment 55 passes into contact with the roller, there will be a substantially uniform transfer of the adhesive to such active face, and through the general arrangements heretofore pointed out, this adhesive on the active face of 60 the segment is transferred to the label or stamp. In addition to the control thus provided by scraper 36^a, the adhesive conditioning of the label or stamp is also controlled by the particular configuration of the active 65 face of the segment, this configuration be-

ing adapted to locate the adhesive only at predetermined portions of the stamp.

As will be understood, the direction of advance of the individual stamps is at right angles to the direction of the axis of rotation of the segment, so that the particular zone of the segment which may be active with any advancing stamp has its direction of length extending transverse to the direction of length of the segment, and advantage is taken of this fact to provide for giving a more or less stencilled application of the adhesive to a stamp. And while the particular form which the stencil may take may be varied to meet different exigencies of use, 80 we have shown a simple arrangement which will meet this problem, this arrangement providing for giving the stencil the form of a plurality of parallel stripes, this effect being provided by employing one or more 85 grooves or depressions 37^a intermediate and parallel to the sides of a particular zonal portion, thus giving a striped appearance to the adhesive coating. While this has the effect of partially meeting the possibilities 90 of spreading of the adhesive during stamp application, the main solution to this problem of oozing is provided by definitely defining the width of the zonal portion of the active face of the segment by the use of additional grooves 37^b on the segment face, which grooves practically correspond in position to the line of severance between adjacent stamps, the width of these grooves 37^b being sufficient to locate the active face portion 95 100 at a point more or less spaced from the side edge of a stamp or label. In other words, the over-all width of the active face operating on an individual stamp is less than the width of the stamp itself, spaces 105 being left at the side edges of the stamps within which no adhesive is applied, so that any tendency of the stripes to spread outwardly will simply place the adhesive onto these uncoated edge portions and thus prevent actual oozing of the adhesive from beneath the stamp. In addition, the length of a zonal portion from front to rear of the segment is made less than the length of the stamp, with the general operation of the 110 several mechanisms described so arranged 115 that the stamp and applying face of the segment are brought into operation under such conditions that an uncoated margin will be left at both ends of the stamp, thus providing a continuous marginal portion of the stamp which remains uncoated during the adhesive applying operation, this marginal portion being free to take up any surplus adhesive which may be spread during the 120 stamp applying operation, whether the latter be by a wiping action or other form of application. As will be understood, the 125 ability to provide for this desired stencilling action is more or less dependent upon the ac- 130

curate registration of the applying faces of the segment and the stamps, and this is had through the general timing relation of parts and the provision of the plural revolution 5 operation of the segment heretofore pointed out, the latter making possible the necessary accurate timing relation between the travel of the segment and of the stamp transfer mechanism so as to insure that the stamp carrying heads and the segment faces will come into conjunctive relation at the substantially exact periods desired, without, however, making impossible the use of a safety device which will prevent the application 10 of adhesive to an uncoated carrier head. This will be clear from the fact that while, under such abnormal conditions, the segment is temporarily maintained out of the applying zone, this action is permitted 15 without disturbing the normal timed relation between the parts, the timing relation remaining constant under all conditions, the operation simply making one revolution of the drive mechanism—the timing control 20 extending to the drive connections of the segment rather than to the segment itself—without a corresponding revolution of the segment, so that when this revolution is 25 completed the connection between the segment and its drive is resumed.

From the above it will be readily understood that not only is the preparation of the stamp provided during continuous advancing movement of the stamps or labels, but 30 in addition this action is had by the use of mechanisms in which the stamps are advancing in the direction of their planes—in a horizontal plane corresponding to the plane of the direction of length of the stamp on 35 the carrier head—and with the adhesive applying mechanism operative in a fixed path of travel. By advancing the stamps in directions corresponding to their planes, no liability is had of dislodgment though the 40 carriers are advancing at considerable speed; and since the axis of rotation of the segment is fixed so that the segment movement is in a circular path, assurance is had that the active 45 face of the segment will be in proper position for adhesive application whenever the control mechanism permits the carrier heads and active faces to be brought into 50 conjunctive relation.

As heretofore pointed out, the carrier may 55 be provided with two spaced portions having openings connected with the suction line, thus isolating the points where suction is made active upon the stamp. This would provide an intermediate space within which 60 the stamp would not be supported during the adhesive application, and to meet this condition—and at the same time take care of conditions at the applying station—we locate within this space a supplemental member 65 14^g yieldably mounted, this member pro-

viding the support for the intermediate portion of the stamp at this time. No detailed description of the head in this respect is made herein as the same is more particularly referred to in connection with a companion 70 application wherein the carriers are more specifically claimed.

In order that unequal distribution of adhesive on the stamp or label may be prevented through the possibility of collection 75 of adhesive in the several grooves 37^a and 37^b, we prefer to employ a scraper element 37^c having an active face complementary to the face of a section taken longitudinally through the segment, said element being in 80 the form of a plate located at a point where its active face will co-operate with the segment in the travel of the latter from its position of contact with roller 36 and the point where the segment begins its registration 85 with the advancing carriers. The active face of the element is so formed as to remove surplus adhesive that might enter into grooves 37^a and 37^b so that as the segment comes into its registration position, the 90 grooves will be substantially free from adhesive and therefore practically incapable of delivering adhesive onto the positioned stamp or label, thus insuring that the proper stencilled effect will be provided on the 95 stamp. As element 37^c has its active face located above the adhesive reservoir—see Figure 1—the adhesive which may be removed by the element will be returned to 100 this reservoir.

The gumming device may also be provided with fixed stripping fingers 37^d, the ends of which ride in the notches of the segment, the upper faces of the fingers being located in the plane of travel of the lower 105 faces of the stamps, so that when the stamps are carried across the face of the segment the fingers will operate to strip the stamps therefrom and prevent their being carried down out of contact with the suction pickers. These fingers are preferably connected to a fixed bar 37^e mounted transversely on the supply receptacle 35.

The terms stamp and label in the specification and claims are not intended to be restrictive to special forms of attached sheets, it being obvious that the device is applicable to the attachment broadly of sheet material to articles.

As will be understood, the disclosure presented herein while preferred and especially applicable for the purpose indicated, may be varied to meet the exigencies of use and service, and hence the disclosure may be considered as more or less illustrative, and we desire it to be understood that such changes or modifications as may be found necessary or desirable to render the invention applicable to general use, are reserved and may be made, in so far as the same may 120 125 130

fall within the spirit and scope of the broad invention herein disclosed as more particularly pointed out in the appended claims when broadly construed.

5. What we claim is:—

1. An apparatus for preparing labels or stamps for application to commodity containers, label or stamp transfer mechanism movable between a label or stamp supply station and an applying station, said mechanism including a carrier operative to support the label or stamp by a pneumatic action, said carrier having its movements between said stations in a substantially single plane, adhesive-applying means operative on the label or stamp during the travel of the carrier in such plane, said means including a segment mounted to rotate in a circular path and having a portion of such path of movement located relative to the carrier path of travel to produce a zone of activity of the segment in such travel path, and means for imparting more than a single movement of said segment through such zone location during a single cycle of carrier movement.

2. An apparatus for preparing labels or stamps for application to commodity containers, label or stamp transfer mechanism movable between a label or stamp supply station and an applying station, said mechanism including a carrier operative to support the label or stamp by a pneumatic action, said carrier having its movements between said stations in a substantially single plane, adhesive-applying means operative on the label or stamp during the travel of the carrier in such plane, said means including a segment mounted to rotate in a circular path and having a portion of such path of movement located relative to the carrier path of travel to produce a zone of activity of the segment in such travel path, and means for imparting more than a single movement of said segment through such zone location during a single cycle of carrier movement with the movements of the segment and carrier relatively timed to produce but a single concurrent location of both elements in said zone during the carrier cycle.

3. An apparatus for preparing labels or stamps for application to commodity containers, label or stamp transfer mechanism movable between a label or stamp supply station and an applying station, said mechanism including a carrier operative to support the label or stamp by a pneumatic action, said carrier having its movements between said stations in a substantially single plane, adhesive-applying means operative on the label or stamp during the travel of the carrier in such plane, said means including a segment mounted to rotate in a circular path and having a portion of such path

of movement located relative to the carrier path of travel to produce a zone of activity of the segment in such travel path, and means for imparting more than a single movement of said segment through such zone location during a single cycle of carrier movement with the movements of the segment and carrier relatively timed to produce concurrent location of both elements in said zone solely during the travel of the carrier in its advancing direction.

4. An apparatus for preparing labels or stamps for application to commodity containers, label or stamp transfer mechanism movable between a label or stamp supply station and an applying station, said mechanism including a carrier operative to support the label or stamp by a pneumatic action, said carrier having its movements between said stations in a substantially single plane, adhesive-applying means operative on the label or stamp during the travel of the carrier in such plane, said means including a segment mounted to rotate in a circular path and having a portion of such path of movement located relative to the carrier path of travel to produce a zone of activity of the segment in such travel path, and means for imparting more than a single movement of said segment through such zone location during a single cycle of carrier movement with the movements of the segment and carrier relatively timed to produce concurrent location of both elements in said zone solely during the travel of the carrier in its advancing direction and in the presence of a label or stamp on the carrier.

5. An apparatus for preparing labels or stamps for application to commodity containers, label or stamp transfer mechanism movable between a label or stamp supply station and an applying station, said mechanism including a carrier operative to support the label or stamp by a pneumatic action, said carrier having its movements between said stations in a substantially single plane, adhesive-applying means operative on the label or stamp during the travel of the carrier in such plane, said means including a segment mounted to rotate in a circular path and having a portion of such path of movement located relative to the carrier path of travel to produce a zone of activity of the segment in such travel path, and means for imparting more than a single movement of said segment through such zone location during a single cycle of carrier movement with the movements of the segment and carrier relatively timed to produce but a single concurrent location of both elements in said zone during the carrier cycle, said segment having its movements timed in synchronous speed to the speed of travel of the carrier.

6. An apparatus for preparing labels or

stamps for application to commodity containers, label or stamp transfer mechanism movable between a label or stamp supply station and an applying station, said mechanism including a carrier operative to support the label or stamp by a pneumatic action, said carrier having its movements between said stations in a substantially single plane, adhesive-applying means operative on the label or stamp during the travel of the carrier in such plane, said means including a segment mounted to rotate in a circular path and having a portion of such path of movement located relative to the carrier path to produce a zone of activity of the segment in such travel path, and means for imparting more than a single movement of said segment through such zone location during a single cycle of carrier movement with the movements of the segment and carrier relatively timed to produce but a single concurrent location of both elements in said zone during the carrier cycle, said applying mechanism also including an adhesive supply roller operatively connected to the segment to move concurrently therewith.

7. An apparatus for preparing labels or stamps for application to commodity containers, label or stamp transfer mechanism movable between a label or stamp supply station and an applying station, said mechanism including a carrier operative to support the label or stamp by a pneumatic action, said carrier having its movements between said stations in a substantially single plane, adhesive-applying means operative on the label or stamp during the travel of the carrier in such plane, said means including a segment mounted to rotate in a circular path and having a portion of such path of movement located relative to the carrier path of travel to produce a zone of activity of the segment in such travel path, and means for imparting more than a single movement of said segment through such zone location during a single cycle of carrier movement with the movements of the segment and carrier relatively timed to produce but a single concurrent location of both elements in said zone during the carrier cycle, and control mechanism whereby said concurrent location of the elements is prevented in the absence of a label or stamp on the carrier.

8. An apparatus for preparing labels or stamps for application to commodity containers, label or stamp transfer mechanism movable between a label or stamp supply station and an applying station, said mechanism including a carrier operative to support the label or stamp by a pneumatic action, said carrier having its movements between said stations in a substantially single plane, adhesive-applying means operative on

the label or stamp during the travel of the carrier in such plane, said means including a segment mounted to rotate in a circular path and having a portion of such path of movement located relative to the carrier path of travel to produce a zone of activity of the segment in such travel path, and means for imparting more than a single movement of said segment through such zone location during a single cycle of carrier movement with the movements of the segment and carrier relatively timed to produce but a single concurrent location of both elements in said zone during the carrier cycle, and control mechanism whereby said concurrent location of the elements is prevented in the absence of a label or stamp on the carrier, said control mechanism including a shiftable element movable with the carrier and adapted to control the segment movements, the shifting movements of said elements being between active and inactive positions, the selection of position being determined by the pneumatic conditions in said carrier.

9. An apparatus for preparing labels or stamps for application to commodity containers, and wherein a plurality of labels or stamps are concurrently rendered active, a stamp or label supply station wherein a plurality of labels or stamps are delivered concurrently, stamp or label transfer mechanism movable between the label or stamp supply station and an applying station, said mechanism including a plurality of stamp or label carriers corresponding in number to the number of concurrently delivered stamps or labels with the carriers relatively positioned to locate the stamps or labels in a plane common to the several labels or stamps and to provide travel thereof from one station to the other in substantially such plane, means for applying adhesive to the several positioned labels or stamps concurrently during travel of the carriers, said means including a segmental face mounted to rotate in a fixed path and having a portion of such path located relative to the travel path of the carriers to produce a zone of activity of the face in such travel path, and means for imparting rotating movements to the face support to cause said face to pass through such zone location more than a single time during a single cycle of carrier movements.

10. An apparatus for preparing labels or stamps for application to commodity containers, and wherein a plurality of labels or stamps are concurrently rendered active, a stamp or label supply station wherein a plurality of labels or stamps are delivered concurrently, stamp or label transfer mechanism movable between the label or stamp supply station and an applying station, said mechanism including a plurality of stamp or label carriers corresponding in number to the

- number of concurrently delivered stamps or labels with the carriers relatively positioned to locate the stamps or labels in a plane common to the several labels or stamps and 5 to provide travel thereof from one station to the other in substantially such plane, means for applying adhesive to the several positioned labels or stamps concurrently during travel of the carriers, said means including a segmental face mounted to rotate in a fixed path and having a portion of such path located relative to the travel path of the carriers to produce a zone of activity of the face in such travel path, and means 10 for imparting rotating movements to the face support to cause said face to register with the carriers in said zone solely during the advancing movement of the carriers in the presence of labels or stamps on the carriers. 15 20
11. An apparatus for preparing labels or stamps for application to commodity containers, and wherein a plurality of labels or stamps are concurrently rendered active, a 25 stamp or label supply station wherein a plurality of labels or stamps are delivered concurrently with the stamps or labels connected together in strip form, stamp or label transfer mechanism movable between the 30 label or stamp supply station and an applying station and operative to receive stamps in strip form and deliver them in separated form, said mechanism including a plurality of stamp or label carriers corresponding to the number of stamps or 35 labels forming the strip, and with the carriers relatively positioned to advance the stamps or labels from the supply station to the applying station in a single plane 40 corresponding to the plane of the strip, means for cutting the strip into its individual stamp formation during travel of the carriers, adhesive applying means adapted to apply adhesive to the separated stamps 45 or labels as the advancing movement of the latter continues, such applying means including a rotating segment having individual faces active on the individual stamps, said segment having its movements timed 50 to provide registration of its faces and the carriers solely in the presence of the labels or stamps on the carrier. 55
12. An apparatus for preparing labels or stamps for application to commodity containers, and wherein the label or stamp is advanced from a supply station to an applying station and prepared during travel to the latter station, a carrier movable between said stations and adapted to advance 60 the label or stamp into applying position, and means for applying an adhesive surface to the label or stamp while supported on the carrier and during carrier travel, said means including a movable segment, 65 paths relatively arranged to produce a tangential relation therebetween when both are concurrently advancing through a predetermined point to produce registration contact, said segment having an adhesive applying face of less peripheral extent and area than the similar extent and area of the stamp or label, and means for operating said carrier and segment in such timed relation and in such paths as to maintain the periphery of 70 the active portion of the segment face spaced from the periphery of the advancing stamp or label throughout the period of registration and contact to produce an uncoated marginal portion throughout the periphery of the stamp or label. 75 80
13. An apparatus for preparing labels or stamps, and wherein a plurality of labels or stamps are advanced from a supply station to an applying station and prepared en route, and wherein the stamps or labels are supported by a transfer mechanism traveling between said stations adapted to advance the stamps or labels during travel in one direction, means for concurrently applying an adhesive surface to the several stamps being advanced, said means including a segment movable to advance with the passing stamps and having a length to cooperate with each of the stamps carried, said segment having a facial configuration to produce a plurality of active applying zones corresponding to the number of stamps being transferred, with the zone boundary arranged to prevent adhesive application at 90 the opposite side margins of the advancing stamps or labels. 95 100
14. An apparatus for preparing labels or stamps, and wherein a plurality of labels or stamps are advanced from a supply station to an applying station and prepared en route, and wherein the stamps or labels are supported by a transfer mechanism traveling between said stations adapted to advance the stamps or labels during travel in one direction, means for concurrently applying an adhesive surface to the several stamps being advanced, said means including a segment movable to advance with the passing stamps and having a length to cooperate with each of the stamps carried, 105 said segment having a facial configuration to produce a plurality of active applying zones corresponding to the number of stamps being transferred, with the zone boundary arranged to prevent adhesive application at the opposite side margins of the advancing stamps or labels, each zone having a length in a different dimension 110 115 less than that of the stamp in the same dimension, and means for synchronizing the movements of segment and transfer mechanism to produce registration contact of the 120 125

advance portion of the zones and the several stamps or labels at a point spaced from the advance edge of the labels.

15. An apparatus for preparing labels or stamps, and wherein a plurality of labels or stamps are advanced from a supply station to an applying station and prepared en route, and wherein the stamps or labels are supported by a transfer mechanism traveling between said stations adapted to advance the stamps or labels during travel in one direction, means for concurrently applying an adhesive surface to the several stamps being advanced, said means including a segment movable to advance with the passing stamps and having a length to cooperate with each of the stamps carried, said segment having parallel grooves extending transverse to the direction of length of the segment to produce a plurality of applying zones of definite width in such segment length, said grooves being spaced a distance such as to render a zone of less width than the width of the stamp or label with which it cooperates, the travel paths of stamp or label and zone being relatively arranged as to locate the opposite side edges of a stamp at intermediate points in the width of the defining grooves of its zone, whereby marginal side edges of the stamp will remain uncoated.
- 10 15 20 25 30 35 40 45 50 55 60
16. An apparatus for preparing labels or stamps, and wherein a plurality of labels or stamps are advanced from a supply station to an applying station and prepared en route, and wherein the stamps or labels are supported by a transfer mechanism traveling between said stations adapted to advance the stamps or labels during travel in one direction, means for concurrently applying an adhesive surface to the several stamps being advanced, said means including a segment movable to advance with the passing stamps and having a length to cooperate with each of the stamps carried, said segment having a facial configuration to produce a plurality of active applying zones corresponding to the number of stamps being transferred, with the zone boundary arranged to prevent adhesive application at the opposite side margins of the advancing stamps or labels, each zone having a length in a different dimension less than that of the stamp in the same dimension, and means for synchronizing the movements of segment and transfer mechanism to produce registration contact of the advance portion of the zones and the several stamps or labels at a point spaced from the advance edge of the labels and with the rear edge of the zone spaced from the corresponding edge of the stamp or label, whereby each stamp will have its marginal portions free from adhesive coating.
- 40 45 50 55 60
17. An apparatus for preparing labels or stamps, and wherein a plurality of labels or stamps are advanced from a supply station to an applying station and prepared en route, and wherein the stamps or labels are supported by a transfer mechanism traveling between said stations adapted to advance the stamps or labels during travel in one direction, means for concurrently applying an adhesive surface to the several stamps being advanced, said means including a segment movable to advance with the passing stamps and having a length to cooperate with each of the stamps carried, said segment having parallel grooves extending transverse to the direction of length of the segment to produce a plurality of applying zones of definite width in such segment length, said grooves being spaced a distance such as to render a zone of less width than the width of the stamp or label with which it cooperates.
- 55 60

18. Means for adhesively preparing a stamp or label for application during travel of the label or stamp en route to the point of application, a stamp or label transfer mechanism having means for supporting the stamp or label by pneumatic action, a rotatable element carrying the adhesive applying face and having a path of movement to bring said face into registration with the travelling stamp or label, and means for controlling the rotation of said element, said means including a constantly rotating drive element, a shaft for rotating the element, and connections between said drive element and the shaft to normally provide shaft movements in unison with the drive element and movable to temporarily break the drive connection therebetween, and means controlled by the presence or absence of a stamp or label on the advancing transfer mechanism and operative in the presence of the pneumatic action for selectively determining the position of said connections.
- 90 95 100 105 110 115 120 125
19. Means for adhesively preparing a stamp or label for application during travel of the label or stamp en route to the point of application, a stamp or label transfer mechanism having means for supporting the stamp or label by pneumatic action, a rotatable element carrying the adhesive applying face and having a path of movement to bring said face into registration with the travelling stamp or label, and means for controlling the rotation of said element, said means including a constantly rotating drive element, a shaft for rotating the element, said shaft carrying a pawl adapted to engage the recess of the drive element to form a drive connection between the drive element and the shaft, said pawl being normally in engagement with the recess and movable in a path concentric with the drive axis, and

means carried by the transfer mechanism and adapted to cooperate with the pawl to release the latter from its recess, said latter means being normally in position to break 5 such connection and shiftable from such position in the presence of a stamp or label properly positioned in the transfer mechanism.

20. Means for adhesively preparing a 10 stamp or label for application during travel of the label or stamp en route to the point of application, a stamp or label transfer mechanism having means for supporting the stamp or label by pneumatic action, a rotatable element carrying the adhesive applying face and having a path of movement to bring said face into registration with the travelling stamp or label, and means for controlling the rotation of said element, said 15 20 means including a constantly rotating drive element, a shaft for rotating the element, said shaft carrying a pawl adapted to engage the recess of the drive element to form a drive connection between the drive element 25 and the shaft, said pawl being normally in engagement with the recess and movable in a path concentric with the drive axis, and means carried by the transfer mechanism and adapted to cooperate with the pawl to 30 release the latter from its recess, said latter means being normally in position to break such connection and shiftable from such position in the presence of a stamp or label properly positioned in the transfer mechanism, and means operatively connected to the pneumatic system for controlling the shifting action.

21. Means for adhesively preparing a stamp or label for application during travel 40 of the label or stamp en route to the point of application, a stamp or label transfer mechanism having means for supporting the stamp or label by pneumatic action, a rotatable element carrying the adhesive applying face and having a path of movement to bring said face into registration with the travelling stamp or label, and means for controlling the rotation of said element, said 45 means including a constantly rotating drive element, a shaft for rotating the element, said shaft carrying a pawl adapted to engage the recess of the drive element to form a drive connection between the drive element 50

and the shaft, said pawl being normally in engagement with the recess and movable in a path concentric with the drive axis, and means carried by the transfer mechanism and adapted to cooperate with the pawl to release the latter from its recess, said latter means being normally in position to break 55 such connection and shiftable from such position in the presence of a stamp or label properly positioned in the transfer mechanism, said latter means including a pivoted lever having an arm adapted to travel 60 through the path of travel of said pawl, said lever having a normal position to carry said arm into said path of travel, said latter means being also operatively connected to the pneumatic system to cause lever movements to carry said arm out of such path of travel in the presence of the properly positioned stamp or label.

22. In a stamp applying machine, means for holding a stamp and adhesive applying 75 device having an adhesive carrying surface of less area than the surface of the stamp, means for furnishing adhesive to the surface of the applying device, means for bringing said surface in contact with the stamp and 80 means for removing surplus adhesive from the edges of the surface before contact with the stamp.

23. In a stamp applying machine, a travelling stamp carrier, means for holding a 85 stamp on the carrier, means for applying adhesive to the stamp normally maintained in operative position during the active travel of the carrier and means for automatically rendering the adhesive applying device in- 90 operative in the absence of a stamp on the carrier operable by the holding device.

24. In a stamp applying machine, a travelling stamp carrier, suction means for holding a stamp on the carrier, means for applying adhesive to the stamp normally maintained in operative position during the active travel of the carrier and means operable through the suction means for rendering the adhesive applying device inoperative 95 in the absence of a stamp on the carrier. 100

In testimony whereof we have hereunto set our hands.
